WASHING MACHINE

Lewis A. James, Independence, Kans.

Application April 1, 1935, Serial No. 14,025

13 Claims. (Cl. 68—15)

This invention relates to washing machines and has for its principal objects to provide a simple, inexpensive agitator and tub construction designed to wash and thoroughly cleanse such articles as dishes, clothes, fabrics and other similar materials; to provide improved agitation of the washing liquid wherein the slushing action thereof acts directly upon the articles being washed without subjecting them to the rigorous action of the impeller or agitator mechanism; to provide for adjustment of the supporting legs of the tub; to provide an improved mechanism for operating the agitator either manually or by the power of a prime mover; and in the instance of washing dishes or other frangible articles to provide the tub with a removable supporting tray.

In accomplishing these and other objects of the invention, as hereinafter pointed out, I have provided improved details of structure, the preferred forms of which are illustrated in the accompanying drawings wherein:

Fig. 1 is a perspective view of a washing machine embodying the features of the present invention, parts of which are broken away to better illustrate the construction thereof.

Fig. 2 is a vertical cross section through the machine on the line 2—2, Fig. 3.

Fig. 3 is a vertical longitudinal section through the machine on the line 3—3, Fig. 2.

Fig. 4 is a vertical cross section similar to Fig. 2 but showing the tray and lid of the tub removed to better illustrate the agitator and its operating mechanism.

Fig. 5 is an enlarged section through one end of the tub, particularly illustrating the agitator operating mechanism.

Fig. 6 is a detail section on the line 6—6, Fig. 4, illustrating the method of attaching the legs to the tub.

Fig. 7 is a detail perspective view of the agitator and its operating lever.

Fig. 8 is an end view of a modified form of washing machine equipped with a mechanical drive operable by a suitable prime mover.

Fig. 9 is a detail section of a portion of a modified form of tub employing a wringer support.

Referring more in detail to the drawings:

1 designates a washing machine constructed in accordance with the present invention and which includes a tub 2 having vertical side walls 3—4 interconnected by a substantially semi-cylindrical bottom 5, and having end walls 6—7 connected to the vertical portions of the side walls, the end walls being provided with semi-

circular lower portions 8 connected with the rounded bottom 5 by flanged seams 9, as best illustrated in Fig. 6.

The side walls 3—4 are flanged outwardly as at 10 and 11 and then upwardly at 12 and 13 to provide horizontal ledges 14 to support a tray 15, later described, and to form offset vertical flanges 16 and 17 for retaining the cover 18, later described. The upper edges of the end walls 6—7 are bent retractively in the plane of the upper edges of the off-set flanges 16 and 17 into contact with the inner faces thereof and then inwardly as at 19 and 20 in the plane of the ledges 14 to provide inwardly extending flanges 21 and 22 cooperating with the ledge flanges in supporting the tray.

The open top 23 of the tub defined by the flanges 16 and 17 and the upper edges of the end walls 6—7 is closed by the removable cover 18 that is shaped to conform to the opening, and has depending flanges 24—25 on the side and end edges thereof telescoping within the side flanges and end walls of the tub to rest upon the ledges 14 as best shown in Fig. 2. To aid in application and removal of the cover it is provided with a suitable handle 26.

The tub thus described is supported from the ends thereof by pairs of legs 27—28 and 29—30 that are secured to the end walls of the tub by plates 31 having lateral flanges 32 terminating in downwardly extending lips 33 to extend over the upper ends of the legs as best illustrated in Figs. 1 and 2, the upper ends of the legs being attached to the plate and tub by fastening devices, such as bolts 34 extending through the leg plates and end walls of the tub. The legs are also attached to the tub by U-shaped clips 35 having ends 36 engaging in the seams 9 that connect the end walls of the tub with the bottom 5 and which have inwardly extending foot portions 37 engaging the inner faces of the legs as shown in Fig. 6. The clips are retained in clamping position with the legs and with the seam of the tub by bolts 38 having shanks 39 extending through openings 40 in the clips and through 45 aligning openings 41 in the legs, the heads 42 of the bolts being retained against the clips by nuts 43 threaded on the shanks of the bolts and engaging the outer faces of the legs.

Mounted within the tub is an agitator 44 including a flat bar or paddle 45 extending longitudinally of the tub and having its ends rigidly connected with hangers 46 and 47. The hangers 46 and 47 comprise plates of substantial width and of sufficient length to mount the bar 45 for 55

swinging oscillatory movement over the bottom of the tub, the upper ends of the hangers being pivoted in the axis of the bottom of the tub on studs 48 including bearing portions 49 extending through openings 50 in the ends thereof, and having heads 51 engaging the inner face of the arms. The opposite ends of the bearing portions terminate in reduced shanks 52 to form shoulders 53 to engage against the inner face of the tub when the shanks are projected through openings 54 formed in the axis of the semi-circular bottom.

In order to freely mount the hangers for swinging movement over the end walls of the tub, the bearing portions of the studs carry washers 55 for spacing the hangers from the end wall of the tub. When the studs are in place in the openings they are secured by nuts 56 threaded on the projecting ends thereof and engage washers 57 which co-operate with the shouldered portion of the studs to clamp against the inner and outer faces of the end wall, as shown in Fig. 5.

In order to oscillate the agitator through substantially 180°, as shown by the dotted lines in Fig. 4, I provide an actuating rock lever 58 that is pivotally and slidably mounted on a fulcrum 59. The fulcrum 59 includes a roller 60 that is rotatably mounted on the head of a stud 61 similar to the studs mounting the agitator arms, the stud 61 being located substantially above the stud 30 mounting the agitator arm 46 in an opening 62 formed in the end wall of the tub. The stud is clampingly retained in the opening by means of a shoulder 63 formed thereon to engage the inner face of the wall and a washer 64 retained in engagement with the outer face of the wall by a nut 65. The roller 60 is mounted on the bearing portion 66 of the stud and has a recess 67 in the face thereof for countersinking the head 68 of the stud. The outer face of the head 68 of the stud thus lies in the plane of the roller face so that it does not interfere with sliding movement of the actuating lever thereover, as now described.

The actuating lever includes a substantially channel-shaped guide portion 69 comprising spaced side flanges 70 and 71 connected by a web 72. The outer edges of the flanges 70 and 71 are bent inwardly to form lips 73 and 74 to engage the inner face of the roller 60 that operates between the side flanges 70 and 71.

Fixed to the web 72 of the guide channel and depending from its lower end is a plate 75 of greater width than the channel to provide laterally extending wings or guards 76 and 77 which tend to prevent the garments or articles being washed from catching between the operating lever and its fulcrum roller.

The upper end of the guide section terminates in a handle portion 78 projecting from the top of the tub so that the lever may be conveniently rocked on the fulcrum roller 60.

In order to accommodate the lever, the inwardly extending flange 21 on that end of the tub is cut away as at 79, and the cover 18 is provided with an aligning notch 80 through which the operating portion of the lever extends, as best illustrated in Fig. 1. The lower end of the plate 75 is provided with a suitable opening 81 to pivotally connect with a stud 82 carried by the hanger 46 of the agitator at a point substantially above the agitating bar 45.

It is thus apparent that when the handle is oscillated back and forth, the pivotal connection of the operating lever with the plate 46 causes reverse oscillation of the agitator upon its pivots 75 51, as shown by the dotted lines in Fig. 4. Due

to the off-center relation of the pivotal connections 51-82 of the agitator and the fulcrum roller 60, the lever is caused to slide or reciprocate upon the fulcrum as the agitator approaches its upper limits of travel. This is an important feature of the present invention, because it allows for full 180° movement of the agitator with a lesser angle of movement of the rocker arm.

Upon oscillation of the agitator across the bottom of the tub, the washing liquid is caused to move ahead of the paddle bar and to fall back thereover toward the opposite wall of the tub in wave-like formation, and upon reverse movement of the paddle the washing liquid is impelled in reverse direction to produce a back and forth swishing action of the liquid across the articles being washed.

In order to wash dishes and other frangible objects in the machine, I provide a tray 83 having end plates 84 and 85 of suitable width to slide freely between the side walls 3-4, and having semi-circular depending portions 86 and 87 of smaller radius than the bottom of the tub to allow clearance for the agitator. The upper portions of the end plates are connected by side walls 88 and 89 extending upwardly from the horizontal diameter of the semi-circular portions to the ledge portions 14, where the walls are flanged laterally, as at 90 and 91, to suspendingly support the tray within the tub. The semi-circular portions of the end plates are connected by an arcuate partition 92 forming an arcuate agitating chamber 93 in which the agitator oscillates. The upper edges 94 and 95 of the partition terminate in the horizontal plane of the lower edges of the side plates to form elongated openings 96 and 97 therebetween, through which the water is impelled under the oscillating force of the agitator to fall back upon the dishes contained in the tray. The semi-cylindrical bottom of the tray is provided with a series of openings 98 to allow return of the washing liquid to the agitating chamber.

In Fig. 8 is shown a modification of the invention wherein the agitator is operated by a suitable prime mover (not shown) through a mechanical drive connection with the rocker arm. In this construction, the channel-shaped portion of the rocker arm projects above the tub a sufficient distance to accommodate a roller 100 carried on the upper end of a rock lever 101 that is pivotally mounted on a stud 102 carried on the outer end of the tub and which has a depending arm 103 connected by a pitman 104 with an eccentric pin 105 on the side of a pulley 106. The pulley 106 is rotatably mounted on a shaft 107 carried by one of the legs supporting the tub and is operated by a belt 108 driven by a suitable prime mover such as a motor, not shown.

It is thus apparent that when the pulley is rotated by the belt, the pitman 104 oscillates the lever 103 to rock the agitator lever as previously described. Upon oscillation of the lever 103 the roller 100 reciprocates within the channel-shaped portion of the lever during sliding movement of the rocker arm upon its fulcrum.

In the event that a wringer is to be attached to the tub a substantially rectangular shaped trough 110 can be formed in one end of the tub and equipped with a suitable backing 111 for attaching a wringer, not shown.

In operating a washing machine constructed and assembled as described, and assuming that the tray is in position within the tub, the articles to be washed, such as dishes, are inserted in the

tray and a suitable amount of wash liquid is poured in the tub. Then upon oscillation of the rock lever 58 the agitator is caused to oscillate back and forth within the arcuate chamber in 5 the manner of a piston to alternately propel the wash liquid from the openings 96-97 to produce a back and forth swishing action of the liquid across the articles contained in the tray. As the wash liquid is being propelled at one side of the 10 paddle a suction is produced at the opposite side to enhance the effectiveness of the agitation.

During oscillation of the agitator, the rock lever pivots and simultaneously slides upon the fulcrum roller when the agitator approaches the upper 15 limits of its movement, as shown in dotted lines in Fig. 4, so that the rock lever is caused to move through a shorter arc than the agitator.

As above pointed out, this is an important feature in the present invention, as it provides for 20 full movement of the agitator and at the same time allows for maximum height of the side walls of the tub.

When the washer is to be used for washing clothes or similar articles, the tray can be removed and the clothes placed directly within the 25 tub. Then upon operation of the agitator the swishing action of the water tends to retain the clothes from direct contact therewith, so that they are not subjected to the rigorous action 30 thereof that might cause undue wear of the fabrics.

From the foregoing it is apparent that I have provided a washing machine which is of simple, inexpensive construction and is readily adapted 35 for efficient washing of such articles as dishes, clothes, fabrics, and other similar materials.

What I claim and desire to secure by Letters Patent is:

1. A washing machine including a tub having a 40 substantially semi-cylindrical bottom, a tray in the tub having a similarly shaped bottom spaced from the bottom and sides of the tub to form an arcuate agitating chamber open at the ends, an agitator in the chamber, means swingingly 45 mounting the agitator for oscillatory movement across said chamber to impel wash liquid from said chamber through the open ends thereof to alternately move in opposite directions across articles contained in said tray, an oscillatory lever 50 pivotally connected with said mounting means for the agitator and having a lesser degree of movement than the agitator, and means for mounting the oscillatory lever on the tub to compensate for said difference in movement.

55 2. A washing machine including a tub having a substantially semi-cylindrical bottom, a tray in the tub having a similarly shaped bottom spaced from the bottom and sides of the tub to form an arcuate agitating chamber open at the ends, an 60 agitator in the chamber, means swingingly mounting the agitator for oscillatory movement across said chamber to impel wash liquid from said chamber through the open ends thereof to alternately move in opposite directions across articles 65 contained in said tray, actuating means for the agitator including a fulcrum carried by the tub, a lever pivotally and slidably mounted on the fulcrum, and means pivotally connecting the lever with the agitator.

70 3. A washing machine including a tub having a substantially semi-cylindrical bottom, a tray in the tub having a similarly shaped bottom spaced from the bottom and sides of the tub to form an arcuate agitating chamber open at the ends, an 75 agitator in the chamber including a blade,

hangers connected with the blade and pivotally mounted in the axis of said cylindrical bottom of the tub to suspend said blade for oscillatory movement in said chamber, a lever pivotally connected with one of said hangers, and means for slidably fulcruming the lever on said tub, whereby operation of the lever oscillates said blade to cause the wash liquid to gush from said chamber back and forth over articles contained in said tray.

4. A washing machine including a tub having a substantially semi-cylindrical bottom, an agitator in the tub, means swingingly mounting the agitator for oscillatory movement across said bottom to impel wash liquid in opposite directions 15 over articles contained in said tub, a rocker arm pivotally connected with the agitator, means slidably and pivotally mounting the rocker arm on the tub, a second lever pivoted on the tub and having pivotal sliding connection with the rocker 20 arm, and motor actuated means for actuating the second lever.

5. A washing machine including a tub having a substantially semi-cylindrical bottom, a tray in the tub having a similarly shaped bottom spaced 25 from the bottom and sides of the tub to form an arcuate agitating chamber open at the ends, an agitator in the chamber including a blade, hangers connected with the blade and pivotally mounted in the axis of curvature of said cylindrical bottom of the tub to suspend said blade for oscillatory movement in said chamber, a rock 30 lever pivotally connected with one of said hangers and having a channel-shaped guide, and a roller fixed to the tub at a point above said hangers and operable in said guide for slidably fulcruming the lever on said tub, whereby operation of the lever oscillates said blade to cause the wash liquid to gush from said chamber back and forth over 35 articles contained in said tray.

6. A washing machine including a tub having a substantially semi-cylindrical bottom, an agitator in the tub, means swingingly mounting the agitator for oscillatory movement across said bottom to impel wash liquid in opposite directions 45 over articles contained in said tub, a rock lever pivotally connected with the agitator, means slidably and pivotally mounting the rock lever on the tub, and motor actuated means connected with said rock lever for effecting actuation of the agitator.

7. A washing machine including a tub having a bottom of substantially semi-circular cross section, hangers having pivotal mounting in the axis of said bottom, an agitating member connecting 55 the free ends of said hangers, a rock lever, means pivotally and slidably mounting the rock lever at a point above said pivotal mounting of one of the hangers, and means pivotally connecting said hanger with said lever at a point between said 60 pivotal mounting and the agitating member.

8. A washing machine including a tub having a bottom of substantially semi-circular cross section, an agitator, means swingingly mounting the agitator for oscillatory movement over said bottom through an angle of substantially 180°, a lever pivotally connected with the agitator, means pivotally and slidably mounting the lever on said tub, and motor actuated means connected with said lever for effecting actuation of the agitator.

9. A washer including a tub, an agitator and hanger arms pivotally mounted in the tub for supporting the agitator for swinging movement about a fixed axis, actuating mechanism for the agitator including an actuating lever having one 75

- end projecting into the tub and pivotally connected with one of said hanger arms at a point between the pivotal mounting of said arm and the agitator, and means for pivotally and slidably mounting the lever on the tub.
- 5 10. In a washer including a tub having spaced end walls, an agitator member, hanger arms connected with the agitator member, means swingingly mounting the arms on said end walls of the tub, a lever having its lower end projecting into the tub and pivotally connected with one of said hanger arms at a point below said mounting means, spaced flanges on a side of the lever facing the adjacent end wall and forming a guide track, 15 and a roller carried by said wall and engageable in the guide track for pivotally and slidably mounting the lever.
- 10 15. In a washer including a tub having spaced end walls, an agitator member, hanger arms connected with the agitator member, means swingingly mounting the arms on said end walls of the tub, a lever having its lower end projecting into the tub and pivotally connected with one of said hanger arms at a point below said mounting means, spaced flanges on a side of the lever facing the adjacent end wall and forming a guide track, 20 a roller carried by said wall and engageable in the guide track for pivotally and slidably mounting the lever, and wings projecting from the sides 25 of the lever to prevent clothes from catching between said hanger arm and the lever.
- 25 30. In a washer including a tub having spaced end walls, an agitator member, hanger arms connected with the agitator member, means swingingly mounting the arms on said end walls of the tub, a lever having its lower end projecting into the tub and pivotally connected with one of said hanger arms at a point below said mounting means, spaced members on a side of the lever facing the adjacent end wall and forming a guide track, 20 and a member carried by said wall and engageable in the guide track for pivotally and slidably mounting the lever.

LEWIS A. JAMES. 30
